UNITED STATES PATENT OFFICE.

EARL E. EICKMEYER, OF DAYTON, OHIO, ASSIGNOR TO THE NATIONAL RECORDING PUMP COMPANY, OF DAYTON, OHIO, A CORPORATION OF OHIO.

LIQUID-DISPENSING APPARATUS.

Application filed August 16, 1926. Serial No. 129,395.

This invention relates to liquid dispensing apparatus and is in the nature of an improvement on the dispensing apparatus shown and described in the application for patent filed by me March 14, 1925, Serial No. 15,471.

That apparatus comprises a delivery bowl into which extends a vertically adjustable discharge pipe which communicates with a flexible delivery hose and this discharge pipe and delivery hose constitute the only means by which the liquid may be withdrawn from the bowl. When it is necessary to drain the bowl without making a delivery of liquid the delivery hose is connected with a drain pipe leading back to the storage reservoir.

One object of the present invention is to provide means for correctly registering all liquid actually delivered by the apparatus; and to this end it is a further object to provide a registering device which will be operated according to the adjustments of the discharge pipe and will be correctly operated regardless of the speed at which those adjustments are made.

In the pump of the aforementioned application it is necessary to move the discharge pipe to its lowermost position in order to drain the bowl and when no delivery is made such an adjustment will cause an inaccurate registration on the registering device. It is therefore a further object of the invention to provide means for draining the bowl through the delivery hose when the discharge pipe is in its uppermost position; and, further, to so control said draining means that it will be operative only when the delivery hose is properly connected with the drain.

A further object of the invention is to provide means for preventing the inadvertent movement of the actuating device, which might cause the registering device to be actuated when no delivery was made.

Liquid is introduced into the bowl by means of a pump and if this pump is free for operation at all times it is possible for the operator to deliver a quantity of liquid in excess of that registered by pumping liquid into the bowl after the discharge pipe has been lowered.

A further object of the invention is to provide means for positively locking the pump against operation at all times except when the delivery pipe is in its uppermost position.

Other objects of the invention will appear as the device is described in detail.

In the accompanying drawings Fig. 1 is a side elevation of a dispensing apparatus embodying my invention; Fig. 2 is a vertical sectional view, partly broken away, of the bowl and its associated parts; Fig. 3 is a detail view of the operative connection between the valve in the delivery hose and the drain valve; Fig. 4 is a detail view of the connection between the lock for the pump and the actuating device for the discharge pipe; Fig. 5 is a front elevation of the setting device for the discharge pipe with the handle broken away; Fig. 6 is a side elevation of the setting device, partly in section; Fig. 7 is a section taken on line 7—7 of Fig. 6; Fig. 8 is a detail view of the pump actuating device and lock; Fig. 9 is a plan view of the controlling mechanism for the actuating device for the discharge pipe; Fig. 10 is a side elevation of said controlling mechanism and of the register; Fig. 11 is a detail showing the actuating device for the register in end elevation; Fig. 12 is a side elevation, partly in section, of the means for connecting the delivery hose with the drain pipe and for controlling the drain valve; Fig. 13 is a section taken on the line 13—13 of Fig. 12; and Fig. 14 is a detail view of the nozzle showing the flange and the key recess in plan.

In these drawings I have illustrated one embodiment of my invention but it will be understood that this particular embodiment has been chosen for the purpose of illustration only and that the mechanism may take various forms without departing from the spirit of the invention.

As here shown, the apparatus comprises a delivery bowl 1 preferably comprising a transparent cylindrical wall mounted on a suitable base 2. The delivery bowl is carried by a hollow standard 3 upon the upper end of which the base 2 for the delivery bowl is mounted. Mounted in the lower portion of the hollow standard is a pump 4 with which is connected an inlet pipe 5 the upper end of which extends into the bowl and is, in the present instance, provided with a downturned end portion or goose neck 6. The bowl may be of any suitable capacity and, in the present instance, has a measuring capacity of ten gallons. Mounted within the bowl is an overflow pipe 7 the open upper end of which is arranged at the ten gallon level within the bowl so that all liquid pumped into the bowl in excess of ten gal-

lons will escape through the overflow pipe. This overflow pipe extends downwardly from the hollow standard and is connected at its lower end with a drain pipe 8 which leads back to the storage reservoir. Slidably mounted in the base 2 of the bowl is a discharge pipe 9 the lower portion of which extends into and is in open communication with a well 10 depending from the lower end of the base. A delivery pipe 109 is in open communication with the well, and consequently with the discharge pipe, and a flexible delivery hose 110 is connected with this delivery pipe and is provided with a nozzle 111 for connecting the same with a tank of an automobile, or other receptacle, to which the liquid is to be delivered. The liquid can be returned to the storage tank from the bowl 1 through this delivery hose and for this purpose the hose is connected with the drain pipe 8. Connected with the drain pipe 8 is an inlet chamber or socket 113 adapted to receive the nozzle 111. The flow of liquid through the delivery pipe and hose is controlled by a valve 114 which, in the present instance, is operated by a shaft 115 having secured thereto a handle 116 and having extending from that side thereof opposite the handle 116 a weighted arm 117 to hold the valve normally in its closed position. The discharge pipe may be adjusted to various positions within the bowl to cause the discharge of the desired quantity of liquid. Preferably the bowl is provided with indicators, as shown at 12, to indicate to the operator and customer the amount of liquid that will be delivered through the discharge pipe when the latter is in an adjusted position. Inasmuch as the bowl is first filled to capacity and the discharge pipe then lowered to the desired position the indicators 12 are graduated from top to bottom so that when the discharge pipe is in line with the zero indication no liquid will be discharged therethrough and when it is in line with the ten gallon indication ten gallons of liquid will be delivered therethrough. Preferably the upper end of the discharge pipe will be arranged slightly above the ten gallon level of the liquid in the bowl when the pipe is in its uppermost position and, if desired, means may be provided for closing the upper end of the discharge pipe when it is in its uppermost position so as to prevent liquid from splashing into the same while the bowl is being filled. As here shown, a cap 13 is slidably mounted in the top of the bowl in line with the upper end of the discharge pipe and is pressed downwardly by a spring 14 so that when the discharge pipe is moved to its uppermost position it will engage this cap and the cap will be held in firm contact therewith. The discharge pipe may be actuated in any suitable manner. As here shown, a rod 15 is connected with the

lower end of the pipe and extends through a stuffing box 16 at the lower end of the well 10. The outer end of this rod is connected with a bracket 17 which is slidably mounted on a guide rod 18 and has connected therewith a toothed bar or rack 19 which meshes with a gear 20 secured to a shaft 21 mounted in the hollow standard, and secured to this shaft on the outer side of the housing is an operating handle 22 by means of which the actuating device, that is, the rack 19 and gear 20, may be manipulated to secure the proper adjustment of the discharge pipe.

If desired, a suitable indicating device or dial may be associated with the operating handle 22 to enable the operator to determine the position of the discharge pipe without the necessity of looking up at the bowl, which is usually located above his head. As shown in Figs. 1, 5 and 6, this dial is provided with a plurality of indications numbered from 1 to 10 inclusive and these indications are so arranged with relation to the handle 22 that when this handle is in line with any one of such indications the discharge pipe will be in line with the corresponding indication 12 on the bowl. In the present device, the handle 22 is provided with an enlarged portion 23 having an opening arranged to be brought into line with any one of the indications, so that the latter will be visible through the opening in the handle. I have in this particular apparatus provided means which may be set to afford a positive stop for the handle when the latter has been moved to a position to set the discharge pipe to deliver the desired quantity of liquid. To this end the several indications associated with the handle 22 are formed on the heads 24 of a series of plungers 25 which are slidably mounted in the walls of a housing 26 mounted within the standard 3 and in line with an opening therein, so that the front wall of this housing in effect constitutes a dial. Rigidly secured to each of the plungers 25 within the housing 26 is a stop 27 which is movable with the plunger into and out of line with a stop finger 28 rigidly secured to the shaft 21. When the plungers are all in their forward or outermost positions all the stops will be out of the path of the stop finger 28 and the shaft may be rotated through a complete revolution. When it is desired to set the discharge pipe to deliver a certain quantity of liquid, say six gallons, the corresponding plunger 25, bearing the indication 6, is pressed inwardly, thus moving the stop 27 to a position near the rear wall of the housing and into the path of the stop arm 28 so that when the handle 22 is moved into line with the indication "6" the stop finger will engage the stop and positively prevent further movement of the handle. In order that the stop may be adjusted to secure absolute accuracy in the position of the discharge pipe I have mounted therein a

100

130

screw 29 which may be adjusted with relation thereto and secured in adjusted positions by means of a lock nut 30, the end of the screw forming the contact portion of the stop which 5 is engaged by the stop arm 28. To prevent any turning movement of the stops about the axes of the respective plungers, each stop has a wide base portion 31 the ends of which rest upon the cylindrical wall of the housing 26 10 on the opposite sides of the plunger, thus permitting free sliding movement of the stop but preventing any displacement thereof when it is engaged by the stop finger 28. Each plunger has formed therein two recesses 15 32 either of which may be engaged by a spring pressed detent 33 carried by the housing 26, which detent serves to hold the plunger against accidental displacement but will yield to permit movement of the plunger 20 when positive pressure is applied thereto. As here shown, means are provided for quickly and easily retracting the plunger which has been operated. This means comprises a lever 34 pivotally mounted on the 25 handle 22 and having its inner end arranged normally in a plane on the inner side of the heads of the plungers, when the latter have been moved inwardly. A spring 35 acting on the other end of the lever holds the inner 30 end thereof normally in this position. Consequently when one of the plungers has been operated and the handle 22 moved into line therewith the end of the lever 34 will lie on the inner side of the head of that plunger and 35 by pressing on the outer end of the lever the plunger may be withdrawn. Thus if the customer desires additional liquid after the quantity originally requested has been delivered the one plunger may be withdrawn and 40 another plunger depressed and the handle moved into line therewith.

Associated with the actuating device for the discharge pipe is a register which will be operated by said actuating device to accurately register the quantities of liquid delivered by the apparatus. This register may take various forms and, as here shown, it 45 comprises a group of counterwheels 36 of a well known construction and which may be provided with transfer mechanism of any suitable kind, this portion of the register forming no part of the invention. Rigidly connected with the units counterwheel of the register is a ratchet wheel 37 which is engaged and actuated by a pawl 38 held in yieldable engagement therewith by a spring 39. The pawl 38 is mounted on a suitable pawl carrier which, in the present instance, is slidably mounted for reciprocatory movement 50 transverse to the axis of the counterwheels. As here shown, the register is mounted within a casing 40 arranged within the hollow standard 3 and having an opening 41 arranged in line with the corresponding opening in the 55 wall of the standard. The pawl carrier is

shown in the form of a slotted plate 42 mounted on pins 43 carried by the housing 40 and having an upwardly extending lug 44 on which the pawl 38 is pivotally mounted. The inner portion 45 of the pawl carrier is pivotally mounted on the body of the pawl carrier for movement about a vertical axis, as shown at 46, and extends into the path of a series of projections or pins 47 carried by the rack 19, which actuates the discharge pipe. These pins are spaced apart such distances that a pin will engage the beveled end of the part 45 of the pawl carrier and actuate the pawl as the end of the discharge pipe is brought into line with each successive indication 12 70 on the bowl, thus causing the register to record the number of gallons of liquid which the discharge tube is set to deliver. The lower side of the part 45 of the pawl carrier is beveled, as shown at 48, in Fig. 11, so that when the rack 19 is moved upwardly to restore the discharge pipe to its normal position the pins will engage this beveled surface of the part 45 and move the same out of the path thereof so that the pawl carrier will not be operated. 75 A spring 49 acting on a pin 50 on the part 45 of the pawl carrier holds the same yieldably in its normal or operative position. In the operation of an apparatus of this kind the rack 19 is sometimes moved very rapidly and should the pawl carrier lag and not move promptly into its operative position a succeeding pin 47 might pass the same without operating the register. I have therefore provided means for positively restoring the pawl 80 carrier to its operative position before a succeeding pin on the rack 19 moves to a position to engage the same. As here shown, a lever 51 is pivotally mounted between its ends within the housing 40 and has one end 85 in contact with the part 45 of the pawl carrier, which in the present arrangement is offset from the body 42 of the carrier. A spring 52 acts on the lower end of the lever to hold the same normally in engagement with the pawl carrier and to move the pawl carrier toward its operative position. The lower end of the lever 51 has a projection or nose 53 which is so arranged that when the pawl 90 carrier is in its normal or operative position this projection will lie out of the path of the pins 47 on the rack and will not be engaged thereby but the movement of the pawl carrier out of its normal position will cause this projection to extend into the path of the pins 95 on the rack so that it will be engaged by one of these pins and the lever will be moved about its axis to positively restore the pawl carrier to its normally operative position. The distance between the projection 53 on the lever 100 and the part 45 of the pawl carrier is 105 less than the distance between adjacent pins 47 on the rack. Consequently when a given pin on the rack actuates the pawl carrier it 110 will pass the projection 53 on the lever before 115

120 125 130

the next succeeding pin moves into a position to engage the pawl carrier and if the spring has not restored the pawl carrier to its normal position it will be positively re-
 5 stored, by the action of the pin on the lever, in time to be engaged by the next succeeding pin. A spring 54 engages the ratchet wheel 36 of the register to prevent the reverse movement thereof and also exerts sufficient pres-
 10 sure on the ratchet wheel to resist the tendency of the register to overthrow due to the rapid operation thereof. I prefer, however, to provide positive means to prevent the overthrow of the register and for this purpose
 15 I have mounted within the casing a cam block 118 which is so arranged that it will be engaged by the end of the pawl 38 as the latter approaches the end of its operative movement, thus causing the tooth of the pawl to be
 20 pressed into engagement with the ratchet wheel and to prevent the overthrow thereof. The handle 22 for the actuating device for the discharge pipe is so arranged that it might be inadvertently moved by the operator, or by
 25 unauthorized persons, to such an extent as to actuate the register when no delivery is made, thus causing a false registration on the register. To avoid this inadvertent operation of the lever I have provided means for so con-
 30 trolling the actuating device that the operator must voluntarily release the same before it can be manipulated. As shown in Figs. 9 and 10 I have mounted on a bracket 55 two pawls 56 and 57 which are independently
 35 movable about a common axis and each of which is movable into and out of engagement with the teeth of the gear 20. A rod 58 is slidably mounted in the bracket 55, extends through the forward wall of the standard 3
 40 and is provided at its outer end with an actuating knob 59. Rigidly secured to this rod, between the pawls 56 and 57, is an abutment 60 arranged to engage projections 61 on the two pawls. The projections are so
 45 arranged that when the abutment 60 is in engagement with one of them it will be out of engagement with the other. Preferably the ends of the abutment are beveled so that it will engage the abutments with a camming
 50 action and move the pawls about their axes. When the rod 58 is in its innermost position, as shown in Figs. 9 and 10, the abutment will be in contact with the projection on the pawl 56 and this pawl will be held in an inopera-
 55 tive position but the pawl 57 will be free for movement and will be held by gravity in contact with the teeth of the gear 20 thus locking that gear against reverse movement. If the actuating mechanism has been oper-
 60 ated to move the stop finger 28 into engagement with one of the fixed stops this will prevent the further forward movement of the handle and consequently it will be positively locked against movement until the operator
 65 actuates either the stop which is limiting the forward movement of the handle or the pawl 57 which prevents the reverse movement of the handle. The handle is thus locked against movement at the end of each delivery and upon the completion of the delivery the operator will draw the rod 58 outwardly, thus causing the abutment to engage the projection 61 on the pawl 57, move that pawl into an inoperative position and permit the pawl 56 to move into engagement with the gear. The gear and handle 22 are thus released for reverse movement but are held against forward movement. When the handle reaches its normal position it is locked against further reverse movement. Any suitable stop may be provided for this purpose but, in the present instance, I have mounted a stop sleeve 62 on the guide rod 18 for the rack 19, this sleeve being arranged between the bracket 17 and a fixed part of the standard, and serving to positively check the reverse movement of the actuating mechanism. Preferably this stop is so arranged that the handle may move in a reverse direction slightly beyond its zero position, the numeral "10" on the dial representing both the zero position and the ten gallon position. By moving the handle slightly beyond the zero position the upper end of the discharge pipe is moved to a position slightly above the ten gallon level in the bowl, as hereinbefore described. When the actuating device is in contact with this stop and the pawl 56 is in contact with the gear the actuating device is again locked against movement in either direction and it is necessary for the operator to manipulate the rod 58 before he can operate the mechanism. The abutment 60 on the rod 58 is so arranged with relation to the stop 61 that it may be moved into an intermediate position in which both pawls will engage the gear, thus positively locking the gear against movement in either direction. The knob 59 is provided with an apertured lug 63 arranged to be moved into line with an apertured lug 64 on the standard 3 when the abutment is in its intermediate position. By inserting a lock 65 through the apertures the rod 58 may be locked in this intermediate position and the actuating mechanism thus locked against all movement.
 If it is necessary to move the discharge pipe to its lowermost position in order to drain the bowl when no delivery is being made a record will be made on the register which does not represent a delivery of liquid. I have therefore provided means for connecting the bowl with the delivery pipe independently of the discharge pipe, which connecting means is so controlled that the connection can be established only when the delivery hose is connected with the drain pipe, thus preventing the delivery of liquid through the delivery hose without the registration of the same on the register. As shown more par-

ticularly in Fig. 2 the bowl is connected with the well 10 by a by-pass 66 which, in the present instance, is formed in the base 2 but which in practice might comprise a separate pipe.

5 A valve 67 is seated at the inner end of this by-pass and its stem extends downwardly through the base and is connected at its lower end with an actuating rod 68. A spring 69 acts on the stem of the valve and rod 68, 10 to hold the valve normally in its closed position. The overflow pipe 7 and the nozzle socket 113 are connected with the drain pipe 8 through a housing 70. Mounted in this housing is a rock shaft 71 with which is 15 rigidly connected an arm 72 which extends into a position in which it will be engaged by the end of the nozzle 111 when the latter has been fully inserted in the socket 113 thus causing the rock shaft 71 to be actuated. A 20 weighted arm 73 is also connected with the rock shaft 71 and tends to hold the arm 72 in its normal or uppermost position. The lower end of the actuating rod 68 for the valve 67 is connected with the weighted arm 73 so that 25 when the nozzle is fully inserted in its socket the valve 67 will be opened, thereby permitting the liquid in the bowl to drain through the delivery hose to the drain pipe. The connection between the socket 113 and the 30 drain pipe 8 is also controlled by a valve which is connected with the rock shaft 71 as set forth in the above mentioned application but as this valve forms no part of the present invention it is not here illustrated. In order 35 that the bowl may be drained it is necessary that both the valve 67 and the valve 114 be opened and I prefer to open both of these valves automatically when the nozzle is inserted in the socket, thus causing the bowl 40 to be drained without further action on the part of the operator. For that purpose I have rigidly secured to the valve actuating shaft 115 an arm 74 the end of which is preferably bifurcated to embrace the actuating 45 rod 68 for the valve 67. This rod is provided with a shoulder 75 which engages the lower side of the arm 74 so that when the rod 68 is operated to open the valve 67 the shoulder 75 will engage the arm 74 and rotate the shaft 50 115 in a direction to open the valve 114. It will be noted, however, that the arm 74 may be moved upwardly relatively to the actuating rod 68, thus permitting of the operation of the valve 114 by the handle 116 without 55 disturbing the valve 67.

To prevent the fraudulent manipulation of the valve 67, when the delivery nozzle is not in the socket 113, as by the insertion of a dummy nozzle or a piece of pipe into the socket, I have provided means for locking the shaft 71 and arm 72 in their normal positions. 60 As shown in Figs. 12 and 13 this lock comprises an arm 76 rigidly secured to the rock shaft 71. A locking lever 77 is pivotally mounted on the housing 70 so that one end 65 thereof may be moved into and out of the path of the arm 76. Preferably the contacting ends of the arm 76 and lever 77 are beveled to facilitate the relative movements thereof. The other end of the lever 77 is connected with a rod or plunger 79 which is slidably mounted in a housing 80 and is held normally in its outermost position, by a spring 81 and when in this position the rod 79 will hold the locking lever 77 in the path of the 70 arm 76 and thus prevent the movement of the valve actuating arm 72. The rod 79 is positively locked in its outermost position and, in the present instance, I have secured to the outer end of the rod a lock 82 which is cylindrical in form and is slidably mounted in the housing 80 and which is provided with a key controlled means for securing the same to the outer end of the housing so as to lock the rod 79 against inward movement. This lock is 85 here shown as of ordinary construction and comprises a key barrel 83 adapted to receive a key 84 by means of which the lock may be manipulated to release the plunger for inward movement. It will be noted that the 90 cylindrical lock casing 82 when in its outermost position extends some distance beyond the end of the socket 113. The nozzle 111 is provided at its outer end with a circumferential flange 85 having an offset portion 86 arranged to engage the projecting lock casing 82 when the nozzle is inserted into the socket. Because of the shapes of the nozzle and of the 95 socket the nozzle can be inserted in the socket in one position only and when in this position the projecting part 82 of the nozzle will engage the end of the lock casing. The key 84 is preferably carried by the projecting portion 86 of the nozzle so that it may be inserted in the key barrel of the lock when the 100 nozzle is inserted in the socket. Preferably the key is retained on the nozzle by means of a spring 87 which will permit of its manipulation to actuate the lock. It will be apparent, therefore, that when the nozzle is inserted 105 within the socket the projecting lock casing will prevent the same from being fully inserted and it will be necessary to insert the key 84 and unlock the rod 79 before the insertion of the nozzle may be completed. In 110 practice the nozzle will be inserted and the key operated and a retaining lever 88 moved into engagement with the flange 85 on the nozzle and pressed downward to force the nozzle fully into the socket to cause it to actuate the shaft 71. The lever 88 has an aperture 89 which may be moved into line with an aperture in a bracket 90 to receive a lock 91, thus permitting the nozzle to be locked in the socket. Obviously it is not essential that the lock casing should project beyond the end of the socket and form a stop for the nozzle but the arrangement is such that the operator 115 will quickly see what is preventing the insertion of the nozzle and will not attempt 120 to do anything to interfere with the lock. The 125 lever 88 is provided with a shoulder 92 which is engaged by a spring 93 which is secured to the bracket 90. The shoulder 92 is positioned so that when the lever 88 is moved into engagement with the flange 85 the shoulder 92 will be moved into line with the aperture 89 so that the lock 91 may be inserted. The lever 88 is provided with a shoulder 94 which is engaged by a spring 95 which is secured to the bracket 90. The shoulder 94 is positioned so that when the lever 88 is moved into engagement with the flange 85 the shoulder 94 will be moved into line with the aperture 89 so that the lock 91 may be inserted. The lever 88 is provided with a shoulder 96 which is engaged by a spring 97 which is secured to the bracket 90. The shoulder 96 is positioned so that when the lever 88 is moved into engagement with the flange 85 the shoulder 96 will be moved into line with the aperture 89 so that the lock 91 may be inserted. The lever 88 is provided with a shoulder 98 which is engaged by a spring 99 which is secured to the bracket 90. The shoulder 98 is positioned so that when the lever 88 is moved into engagement with the flange 85 the shoulder 98 will be moved into line with the aperture 89 so that the lock 91 may be inserted. The lever 88 is provided with a shoulder 100 which is engaged by a spring 101 which is secured to the bracket 90. The shoulder 100 is positioned so that when the lever 88 is moved into engagement with the flange 85 the shoulder 100 will be moved into line with the aperture 89 so that the lock 91 may be inserted. The lever 88 is provided with a shoulder 102 which is engaged by a spring 103 which is secured to the bracket 90. The shoulder 102 is positioned so that when the lever 88 is moved into engagement with the flange 85 the shoulder 102 will be moved into line with the aperture 89 so that the lock 91 may be inserted. The lever 88 is provided with a shoulder 104 which is engaged by a spring 105 which is secured to the bracket 90. The shoulder 104 is positioned so that when the lever 88 is moved into engagement with the flange 85 the shoulder 104 will be moved into line with the aperture 89 so that the lock 91 may be inserted. The lever 88 is provided with a shoulder 106 which is engaged by a spring 107 which is secured to the bracket 90. The shoulder 106 is positioned so that when the lever 88 is moved into engagement with the flange 85 the shoulder 106 will be moved into line with the aperture 89 so that the lock 91 may be inserted. The lever 88 is provided with a shoulder 108 which is engaged by a spring 109 which is secured to the bracket 90. The shoulder 108 is positioned so that when the lever 88 is moved into engagement with the flange 85 the shoulder 108 will be moved into line with the aperture 89 so that the lock 91 may be inserted. The lever 88 is provided with a shoulder 110 which is engaged by a spring 111 which is secured to the bracket 90. The shoulder 110 is positioned so that when the lever 88 is moved into engagement with the flange 85 the shoulder 110 will be moved into line with the aperture 89 so that the lock 91 may be inserted. The lever 88 is provided with a shoulder 112 which is engaged by a spring 113 which is secured to the bracket 90. The shoulder 112 is positioned so that when the lever 88 is moved into engagement with the flange 85 the shoulder 112 will be moved into line with the aperture 89 so that the lock 91 may be inserted. The lever 88 is provided with a shoulder 114 which is engaged by a spring 115 which is secured to the bracket 90. The shoulder 114 is positioned so that when the lever 88 is moved into engagement with the flange 85 the shoulder 114 will be moved into line with the aperture 89 so that the lock 91 may be inserted. The lever 88 is provided with a shoulder 116 which is engaged by a spring 117 which is secured to the bracket 90. The shoulder 116 is positioned so that when the lever 88 is moved into engagement with the flange 85 the shoulder 116 will be moved into line with the aperture 89 so that the lock 91 may be inserted. The lever 88 is provided with a shoulder 118 which is engaged by a spring 119 which is secured to the bracket 90. The shoulder 118 is positioned so that when the lever 88 is moved into engagement with the flange 85 the shoulder 118 will be moved into line with the aperture 89 so that the lock 91 may be inserted. The lever 88 is provided with a shoulder 120 which is engaged by a spring 121 which is secured to the bracket 90. The shoulder 120 is positioned so that when the lever 88 is moved into engagement with the flange 85 the shoulder 120 will be moved into line with the aperture 89 so that the lock 91 may be inserted. The lever 88 is provided with a shoulder 122 which is engaged by a spring 123 which is secured to the bracket 90. The shoulder 122 is positioned so that when the lever 88 is moved into engagement with the flange 85 the shoulder 122 will be moved into line with the aperture 89 so that the lock 91 may be inserted. The lever 88 is provided with a shoulder 124 which is engaged by a spring 125 which is secured to the bracket 90. The shoulder 124 is positioned so that when the lever 88 is moved into engagement with the flange 85 the shoulder 124 will be moved into line with the aperture 89 so that the lock 91 may be inserted. The lever 88 is provided with a shoulder 126 which is engaged by a spring 127 which is secured to the bracket 90. The shoulder 126 is positioned so that when the lever 88 is moved into engagement with the flange 85 the shoulder 126 will be moved into line with the aperture 89 so that the lock 91 may be inserted. The lever 88 is provided with a shoulder 128 which is engaged by a spring 129 which is secured to the bracket 90. The shoulder 128 is positioned so that when the lever 88 is moved into engagement with the flange 85 the shoulder 128 will be moved into line with the aperture 89 so that the lock 91 may be inserted. The lever 88 is provided with a shoulder 130 which is engaged by a spring 131 which is secured to the bracket 90. The shoulder 130 is positioned so that when the lever 88 is moved into engagement with the flange 85 the shoulder 130 will be moved into line with the aperture 89 so that the lock 91 may be inserted.

to force the nozzle into the socket, as he might do if its inward movement were prevented only by the arm 72 on the shaft 71, and which might result in breakage of the parts. When 5 the nozzle is locked in the socket by the lever 88 and the controlling rod 58 for the actuating device is locked in its intermediate position the apparatus is completely locked up and no liquid can be withdrawn therefrom 10 and the register cannot be manipulated.

As has been stated, the liquid is introduced into the delivery bowl by means of a pump and obviously if this pump is free to operate at all times the operator can set the discharge 15 pipe in a lowered position, thus causing the registration of a corresponding amount of liquid, and then, by operating the pump, cause liquid to continue to flow through the discharge pipe in a quantity in excess of that 20 which has been registered. To prevent liquid being thus withdrawn from the apparatus without being registered I have applied to the pump a positive lock which can be released only when the discharge pipe is in its 25 uppermost position, in which position no liquid can enter the same. In the present apparatus, see Figs. 1 and 8, the pump 4 comprises an actuating bar or rack 92 which 30 meshes with a toothed segment 93 rigidly secured to a rock shaft 94, one end of which extends beyond the wall of the standard 3 and has secured thereto an operating handle 95, the manipulation of which will impart reciprocatory movement to the pump 35 actuating rack 92. Pivotaly mounted on a supporting bracket 96 is a locking member 97 which is here shown in the form of an arm having at its lower end projections or teeth 40 98 adapted to engage the internal series of teeth 99 carried by the segment 93. A spring 100 acts on the arm 97 to hold the same normally in locking engagement with the segment, and thus prevent the operation of the latter. In order to positively retain the locking 45 member 97 in locking engagement with the segment I have mounted on the bracket 96 a locking member or tapered block 101 which is movable into a position between the arm 97 and a fixed abutment 102 on the bracket 96 and will engage these parts with a wedging action so as to positively prevent all movement of the arm 97. The arm 97 is provided with an offset portion 103 which contacts with the locking member 101 and 55 which provides for the movement of the arm 97 with relation to the locking member 101 when the latter has been moved out of engagement with said offset portion. The locking member or wedge 101 is rigidly connected 60 with an upwardly extending rod 104 the upper end of which is connected with the actuating device for the discharge pipe in such a manner that the locking member 101 will be moved to an inoperative position only 65 when the actuating device is operated to

move the discharge pipe to its uppermost position. In the present instance, the upper end of the rod 104 is provided with a laterally extending projection 105 which overhangs the upper edge of the bracket 17 of 70 the actuating device and, as here shown, is bifurcated to embrace the rod 15 which connects the actuating device with the discharge pipe and which thus serves to hold the rod 104 against displacement with relation to the 75 bracket during the reciprocatory movement of the latter. A spring 106 acts on the rod 104 and tends to move the same downwardly, that is, in a direction to insert the locking member between the arm 97 and the abutment 80 102. Rigidly connected with the arm 97 is an arm 107 which embraces the rod 104 just above the locking member 101 and which is so arranged with relation to the locking member that the latter will engage the arm 85 107 as soon as it has been moved out of contact with the offset portion 103 of the arm 97, whereby the further movement of the locking member 101 will rock the arm 97 about its axis into an inoperative position with relation to the segment 93. Upon the first downward movement of the discharge pipe the bracket 17 will move downwardly and the spring 106 will move the rod 104 downwardly thus moving the locking member 101 away 95 from the arm 107 and releasing the arm 97 for movement by the spring 100 into its operative position and as soon as the arm 97 has been moved into its operative position the locking member 101 will enter the space between the arm and the abutment 102 and thus positively lock the pump against operation. 100

Having now fully described my invention, what I claim as new and desire to secure by 105 Letters Patent is:

1. In a liquid dispensing apparatus, the combination with a delivery bowl, means for introducing liquid into said bowl, a vertically adjustable discharge pipe extending into said bowl, an actuating device for said discharge pipe, a delivery pipe communicating with said discharge pipe, and a valve to control the flow of liquid through said delivery pipe, of a register, means controlled by said actuating device for operating said register; and means for connecting said delivery bowl with said delivery pipe independently of said discharge pipe. 110

2. In a liquid dispensing apparatus, the combination with a delivery bowl, means for introducing liquid into said bowl, a vertically adjustable discharge pipe extending into said bowl, an actuating device for said discharge pipe, a delivery pipe communicating with said discharge pipe, and a valve to control the flow of liquid through said delivery pipe, of a register, means controlled by said actuating device for operating said register, a by-pass 125 to connect said delivery bowl with said de- 130

livery pipe independently of said discharge pipe, and a valve to control the flow of liquid through said by-pass.

3. In a liquid dispensing apparatus, a delivery bowl, means for introducing liquid into said bowl, a vertically adjustable discharge pipe extending into said bowl, an actuating device for said discharge pipe, a drain pipe leading to a storage receptacle, a delivery hose communicating with said discharge pipe, means for connecting said delivery hose with said drain pipe, a valve to control the flow of liquid through said hose, a register, means controlled by said actuating device for operating said register, means for connecting said bowl with said hose independently of said discharge pipe, a valve to control said connection, and means controlled by the connection of said hose with said drain pipe to 20 actuate the last mentioned valve.

4. In a liquid dispensing apparatus, a delivery bowl, means for introducing liquid into said bowl, a vertically adjustable discharge pipe extending into said bowl, an actuating device for said discharge pipe, a delivery hose communicating with said discharge pipe and having a nozzle, a valve to control the flow of liquid through said hose, a drain pipe leading to a storage receptacle, a socket communicating with said drain pipe and adapted to receive said nozzle, means for connecting said bowl with said delivery hose independently of said discharge pipe, a valve to control said connection, means for holding the last mentioned valve normally in its closed position, and means controlled by the insertion of said nozzle in said socket to move said last mentioned valve to its open position.

5. In a liquid dispensing apparatus, a delivery bowl, means for introducing liquid into said bowl, a vertically adjustable discharge pipe extending into said bowl, an actuating device for said discharge pipe, a delivery hose communicating with said discharge pipe and having a nozzle, a valve to control the flow of liquid through said hose, a drain pipe leading to a storage receptacle, a socket communicating with said drain pipe and adapted to receive said nozzle, means for connecting said bowl with said delivery hose independently of said discharge pipe, a valve to control said connection, an actuating device for the last mentioned valve comprising a weight- 55 ed arm connected with the valve to hold the latter in its closed position, and a trip arm connected with said weighted arm and arranged to be engaged by said nozzle when the latter is inserted in said socket and to move said valve to this open position.

6. In a liquid dispensing apparatus, a delivery bowl, means for introducing liquid into said bowl, a vertically adjustable discharge pipe extending into said bowl, an actuating device for said discharge pipe, a delivery hose

communicating with said discharge pipe and having a nozzle, a valve to control the flow of liquid through said hose, a drain pipe leading to a storage receptacle, a socket communicating with said drain pipe and adapted to receive said nozzle, means for connecting said bowl with said delivery hose independently of said discharge pipe, a valve to control said connection, a locking device to hold the last mentioned valve normally in its closed position, and means controlled by the insertion of said nozzle in said socket to render said locking device inoperative and to actuate said last mentioned valve.

7. In a liquid dispensing apparatus, a delivery bowl, a delivery hose to deliver liquid from said bowl, a nozzle carried by said hose, a valve to control a connection between said delivery hose and said bowl, a drain pipe, a socket communicating with said drain pipe and adapted to receive said nozzle, a pivoted arm operatively connected with said valve, a lever having one end movable into and out of a position to hold said arm normally against movement, means for actuating said lever to move the same into an operative position with relation to said arm, a key actuated lock to control said movement of said lever, and means controlled by the insertion of said nozzle in said socket to actuate said arm and actuate said valve when said lever has been moved to its inoperative position.

8. In a liquid dispensing apparatus, a delivery bowl, a delivery hose to deliver liquid from said bowl, a nozzle carried by said hose, a valve to control a connection between said delivery hose and said bowl, a drain pipe, a socket communicating with said drain pipe and adapted to receive said nozzle, a pivoted arm operatively connected with said valve, a lever having one end movable into and out of a position to hold said arm normally against movement, an actuating rod connected with said lever and so arranged with relation to said socket that it will be actuated by said nozzle when the latter is inserted in said socket, a key actuated lock to control the movement of said rod, and means controlled by said nozzle for imparting movement to said arm after said rod has been actuated by said nozzle.

9. In a liquid dispensing apparatus, a delivery bowl, a delivery hose to deliver liquid from said bowl, a nozzle carried by said hose, a valve to control a connection between said delivery hose and said bowl, a drain pipe, a socket communicating with said drain pipe and adapted to receive said nozzle, a pivoted arm operatively connected with said valve, a lever having one end movable into and out of a position to hold said arm normally against movement, a housing mounted adjacent to said socket, a rod slidably mounted in said housing and connected with said lever, a lock connected with said rod and extending beyond

- the end of said housing and into the path of a part carried by said nozzle, a spring to retain said lever normally in its operative position with relation to said arm, a key carried by said nozzle and so arranged that it can be introduced into said lock only when said nozzle is inserted in said socket, and means controlled by said nozzle for actuating said arm after said rod has been released and actuated.
10. In a liquid dispensing apparatus, a delivery bowl, means for introducing liquid into said bowl, a vertically adjustable discharge pipe extending into said bowl, an actuating device for said discharge pipe, a drain pipe leading to a storage receptacle, a delivery hose communicating with said discharge pipe, means for connecting said delivery hose with said drain pipe, a valve to control the flow of liquid through said hose, a register, means controlled by said actuating device for operating said register, means for connecting said bowl with said hose independently of said discharge pipe, a valve to control said connection, and means controlled by the connection of said hose with said drain pipe to actuate both of said valves.
11. In a liquid dispensing apparatus, a delivery bowl, means for introducing liquid into said bowl, a vertically adjustable discharge pipe extending into said bowl, an actuating device for said discharge pipe, a drain pipe leading to a storage receptacle, a delivery hose communicating with said discharge pipe, means for connecting said delivery hose with said drain pipe, a valve to control the flow of liquid through said hose, a register, means controlled by said actuating device for operating said register, means for connecting said bowl with said hose independently of said discharge pipe, a valve to control said connection, means controlled by the connection of said hose with said drain pipe to actuate the last mentioned valve, and means to cause the first mentioned valve to be opened when said last mentioned valve is opened, said means being such as to permit said first mentioned valve to operate independently of said last mentioned valve.
12. In a liquid dispensing apparatus, a delivery bowl, means for introducing liquid into said bowl, a vertically adjustable discharge pipe extending into said bowl, an actuating device for said discharge pipe, a delivery pipe communicating with said discharge pipe, a valve to control the flow of liquid through said delivery pipe, an actuating device for said valve, means to connect said delivery bowl with said delivery pipe independently of said discharge pipe, a valve to control said connection, an actuating device for the last mentioned valve, and means for connecting said valve actuating devices one with the other that the first mentioned valve will be opened when the last mentioned valve is opened but to permit said first mentioned
- valve to be operated independently of said last mentioned valve.
13. In a liquid dispensing apparatus, a delivery bowl, a vertically adjustable discharge pipe extending into said bowl, an actuating device for said discharge pipe, a delivery pipe communicating with said discharge pipe, a register, means controlled by said actuating device for operating said register, a pump to introduce liquid into said bowl, an actuating device for said pump, a locking member mounted for movement into and out of locking engagement with the actuating device for said pump, an abutment spaced from said locking member, a second locking member arranged to be moved into the space between the first mentioned locking member and said abutment to hold said first mentioned locking member in its locking position, and an operative connection between the last mentioned locking member and the actuating device for said discharge pipe.
14. In a liquid dispensing apparatus, a delivery bowl, a vertically adjustable discharge pipe extending into said bowl, an actuating device for said discharge pipe, a delivery pipe communicating with said discharge pipe, a register, means controlled by said actuating device for operating said register, a pump to introduce liquid into said bowl, an actuating device for said pump, a locking member mounted for movement into and out of locking engagement with the actuating device for said pump, an abutment spaced from said locking member, a second locking member arranged to be moved into the space between the first mentioned locking member and said abutment to hold said first mentioned locking member in its locking position, and an operative connection between the last mentioned locking member and the actuating device for said discharge pipe, said second locking member having means for positively moving the first mentioned locking member to an inoperative position after said second locking member has been moved to an inoperative position.
15. In a liquid dispensing apparatus, a delivery bowl, a vertically adjustable discharge pipe extending into said bowl, an actuating device for said discharge pipe, a delivery pipe communicating with said discharge pipe, a pump to introduce liquid into said bowl, an actuating device for said pump, a pivoted locking member movable into and out of locking engagement with the actuating device for said pump, a second locking member movable into and out of a position to retain the first mentioned locking member in its locking position, and an operating device for said second locking member operatively connected with the actuating device for said discharge pipe.
16. In a liquid dispensing apparatus, a delivery bowl, a vertically adjustable discharge

- pipe extending into said bowl, an actuating device for said discharge pipe, a delivery pipe communicating with said discharge pipe, a pump to introduce liquid into said bowl, an actuating device for said pump, a pivoted locking member movable into and out of locking engagement with the actuating device for said pump, an abutment spaced from the pivoted locking member, a second locking member mounted for movement into and out of the space between said pivoted locking member and said abutment to retain said pivoted locking member in its locking position, and means controlled by the actuating device for said discharge pipe to move said second locking member into an operative position when said discharge pipe is moved to a position in which it can receive liquid from said bowl.
17. In a liquid dispensing apparatus, a delivery bowl, a vertically adjustable discharge pipe extending into said bowl, an actuating device for said discharge pipe, a delivery pipe communicating with said discharge pipe, a pump to introduce liquid into said bowl, an actuating device for said pump, a pivoted locking member movable into and out of locking engagement with the actuating device for said pump, an abutment spaced from said pivoted locking member, a block of metal movable into and out of the space between said abutment and said pivoted locking member to hold the latter in its locking position, an operative connection between said block of metal and the actuating device for said discharge pipe, an arm connected with said pivoted locking member and arranged to be actuated by said block when the latter is moved into an inoperative position.
18. In a liquid dispensing apparatus, a delivery bowl, a vertically adjustable discharge pipe extending into said bowl, an actuating device for said discharge pipe comprising a vertical reciprocating member, a delivery pipe communicating with said discharge pipe, a pump to introduce liquid into said bowl, an actuating device for said pump comprising a part having locking projections, a pivoted locking member having a part movable into and out of engagement with one of the projections on said actuating device, a spring tending to move said locking member into engagement with said projection, an abutment spaced from said pivoted locking member, a locking wedge movable into and out of the space between said abutment and said locking member, a rod connected with said wedge and having a part overhanging the reciprocating member of the actuating device for said discharge pipe, and arranged to be engaged by said reciprocating member just before the latter completes its upward movement, a spring acting on said wedge to move the same into the space between said abutment and said pivoted locking member, and an arm connected with said pivoted locking member and arranged to be engaged by said wedge after the latter has been withdrawn from the space between said abutment and said pivoted locking member.
19. In a liquid dispensing apparatus, a delivery bowl, a vertically adjustable discharge pipe extending into said delivery bowl, a delivery pipe communicating with said discharge pipe, an actuating device for said discharge pipe comprising a gear, a register, means controlled by said actuating device to operate said register, a pair of opposed pawls separately movable into and out of engagement with said gear, and manually operable means to control the positions of said pawls.
20. In a liquid dispensing apparatus, a delivery bowl, a vertically adjustable discharge pipe extending into said delivery bowl, a delivery pipe communicating with said discharge pipe, an actuating device for said discharge pipe comprising a gear, a register, means controlled by said actuating device to operate said register, a pair of opposed pawls separately movable into and out of engagement with said gear, and a slidable rod mounted adjacent to said pawls and having a part movable into a position to hold either of said pawls in an inoperative position or to permit both of said pawls to simultaneously engage said gear.
21. In a liquid dispensing apparatus, a delivery bowl, a vertically adjustable discharge pipe extending into said bowl, a delivery pipe communicating with said discharge pipe, an actuating device for said discharge pipe comprising a gear and a handle connected therewith, a part rigidly connected with said handle, a plurality of stops selectively movable into the path of said part to limit the forward movement of said handle, a pair of pawls separately movable into and out of engagement with said gear, and manually controlled means to cause a selected one of said pawls to engage said gear.
22. In a liquid dispensing apparatus, a delivery bowl, a delivery hose to deliver liquid from said bowl, a nozzle carried by said hose, a valve to control a connection between said delivery hose and said bowl, a drain pipe, a socket communicating with said drain pipe and adapted to receive said nozzle, an actuating device for said valve, a locking device movable into and out of position to hold said actuating device against movement, and means controlled by the insertion of said nozzle in said socket to move said locking device to an inoperative position and release said actuating device for operation.
23. In a liquid dispensing apparatus, a delivery bowl, a delivery hose to deliver liquid from said bowl, a nozzle carried by said hose, a valve to control a connection between said delivery hose and said bowl, a drain pipe, a socket communicating with said drain pipe and adapted to receive said nozzle, an actuating device for said valve, a locking device movable into and out of position to hold said actuating device against movement, and means controlled by the insertion of said nozzle in said socket to move said locking device to an inoperative position and release said actuating device for operation.

ing device for said valve, a locking device movable into and out of position to hold said actuating device against movement, and means controlled by the insertion of said nozzle in said socket to move said locking device to an inoperative position and release said actuating device for operation, said actuating device comprising a part arranged to be operated by said nozzle when the latter is inserted in said socket.

24. In a liquid dispensing apparatus, a delivery bowl, a discharge hose to deliver liquid from said bowl, a nozzle carried by said hose, a valve to control the connection between said delivery hose and said bowl, a drain pipe, a socket communicating with said drain pipe and adapted to receive a nozzle, a pivoted arm operatively connected with said valve, a lever having one end movable into and out of a position to hold said arm normally against movement, an actuating device for said lever comprising a part arranged to be engaged by said nozzle when the latter is inserted in said socket and means to lock said actuating device normally against movement, and means carried by said nozzle to actuate said locking means and release said actuating device for operation by said nozzle.

25. In a liquid dispensing apparatus, a delivery bowl, a vertically adjustable discharge pipe extending into said bowl, an actuating device for said discharge pipe, a delivery pipe communicating with said discharge pipe, a pump to introduce liquid into said bowl, a locking member movable into and out of a position to lock said pump against operation, a second locking member to positively retain the first mentioned locking member in locking position, and means controlled by said actuating device to operate said second locking member.

26. In a liquid dispensing apparatus, a delivery bowl, a vertically adjustable discharge pipe extending into said bowl, an actuating device for said discharge pipe, a delivery pipe communicating with said discharge pipe, a register, means controlled by said actuating device for operating said register, a pump to introduce liquid into said bowl, a locking member movable into and out of a position to lock said pump against operation, a device to positively retain said locking member in locking position, and means controlled by said actuating device to move said retaining device and said locking member to inoperative positions when said discharge pipe is moved to its uppermost position.

27. In a liquid dispensing apparatus, a delivery bowl, a vertically adjustable discharge pipe extending into said bowl, an actuating device for said discharge pipe, a delivery pipe communicating with said discharge pipe, a register, means controlled by said actuating device for operating said register, a pump to introduce liquid into said bowl, an actuating

device for said pump, a locking member movable into and out of locking engagement with said actuating device, a device movable in one direction to positively retain said locking member in locking position and movable in another direction to move said locking member into an inoperative position, and means controlled by the actuating device for said discharge pipe to actuate the last mentioned device.

28. In a liquid dispensing apparatus comprising a delivery bowl, a vertically adjustable discharge pipe extending into said bowl, a delivery pipe communicating with said discharge pipe and an actuating device for said discharge pipe comprising a gear and a handle connected therewith, a part rigidly connected with said handle, a plurality of stops selectively movable into the path of said part to limit the forward movement of said handle, a pair of pawls separately movable into and out of engagement with said gear, a stop to limit the movement of the handle in a reverse direction, and manually controlled means to cause one of said pawls to engage said gear and prevent the reverse movement thereof when said handle is moved in one direction and to cause the other of said pawls to engage said gear and prevent the reverse movement thereof when said handle is moved in the other direction.

29. In a liquid dispensing apparatus, the combination with a delivery bowl, means for introducing liquid into said bowl, a vertically adjustable discharge pipe extending into said bowl, an actuating device for said discharge pipe, a delivery pipe communicating with said discharge pipe, and a valve to control the flow of liquid through said delivery pipe, of means for connecting said delivery bowl with said delivery pipe independently of said discharge pipe.

30. In a liquid dispensing apparatus, the combination with a delivery bowl, means for introducing liquid into said bowl, a vertically adjustable discharge pipe extending into said bowl, an actuating device for said discharge pipe, a delivery pipe communicating with said discharge pipe, and a valve to control the flow of liquid through said delivery pipe, of a by-pass to connect said delivery bowl with said delivery pipe independently of said discharge pipe, and a valve to control the flow of liquid through said by-pass.

31. In a liquid dispensing apparatus, a delivery bowl, means for introducing liquid into said bowl, a vertically adjustable pipe extending into said bowl, an actuating device for said discharge pipe, a drain pipe leading to a storage receptacle, a delivery hose communicating with said discharge pipe, means for connecting said delivery hose with said drain pipe, a valve to control the flow of liquid through said hose, means for connecting said bowl with said hose inde-

pendently of said discharge pipe, a valve to control said connection, and means controlled by the connection of said hose with said drain pipe to actuate the last mentioned 5 valve.

32. In a liquid dispensing apparatus, a delivery bowl, means for introducing liquid into said bowl, a vertically adjustable discharge pipe extending into said bowl, an actuating device for said discharge pipe, a drain pipe leading to a storage receptacle, a delivery hose communicating with said discharge pipe, means for connecting said delivery hose with said drain pipe, a valve to 10 control the flow of liquid through said hose, means for connecting said bowl with said hose independently of said discharge pipe, hereto. 15 a valve to control said connection, and means

controlled by the connection of said hose with said drain pipe to actuate both of said valves. 20

33. In a liquid dispensing apparatus, a delivery bowl, a vertically adjustable discharge pipe extending into said bowl, a delivery pipe communicating with said discharge pipe, an actuating device for said discharge pipe, a register, means controlled by said actuating device for operating said register, a locking device having two parts movable respectively into positions to lock 25 said actuating device against forward movement and against reverse movement, and manually operated means to control the positions of said parts of said locking device. 30

In testimony whereof, I affix my signature

EARL E. EICKMEYER.
